UNITED STATES PATENT OFFICE.

ALFRED A. ZIEGLER, OF BOSTON, MASSACHUSETTS.

ELECTROMAGNET.

1,173,240.

Specification of Letters Patent.

Patented Feb. 29, 1916.

Application filed January 20, 1913. Serial No. 742,989.

To all whom it may concern:

Be it known that I, ALFRED A. ZIEGLER, a citizen of the United States, residing at Boston, in the county of Suffolk and State 5 of Massachusetts, have invented an Improvement in Electromagnets, of which the following is a specification.

This invention relates to electro-magnets, and is intended as an improvement upon 10 the electro-magnet shown in my application #534,932, and #741,650. In my application #534,932 the core of the magnet has a pole-piece at its end and is stationarily supported in upright position on a carrying- 15 plate, and the coil is removably placed on said core, and in said application the core is stationarily supported by screws extended through the pole-piece, and into the carrying- 20 plate.

20 In the construction of relays for railway signaling purposes electro-magnets having their cores formed or provided with enlarged pole-pieces and stationarily supported on the carrying-plate are of consider- 25 able importance, and my present invention has for its object certain improvements in the means for securing the core to the carrying-plate by which the efficiency of the electro-magnet is substantially increased 30 and liability of tampering with the relay reduced.

In accordance with this invention the core is extended through a hole in the carrying- 35 plate, and its pole-piece rests against the under side of said plate, and abutments are arranged on the bottom of the plate which are spaced apart sufficiently to receive the pole-piece between them, and said abutments are made high enough to enable screws to be 40 passed through threaded holes formed in them, the ends of which screws enter recesses formed in the core and bear against seats at the bottoms of said recesses, thus securely fastening the core to the carrying- 45 plate without passing screws through the pole-piece, and thereby utilizing portions of its surface of considerable area for the heads of the screws. Furthermore, said screws are concealed by the housing of which 50 the carrying-plate forms the top wall, which is a decided advantage over passing the screws down through the carrying-plate and into the pole-piece and thereby exposing their heads, whereby they are accessible to 55 those inclined to tamper with the relay. The

carrying-plate which forms the top wall of the housing may be composed of insulating material, of a substantial thickness, having a metallic plate secured to its under side upon which the abutments are formed to receive between them the pole-piece and to serve as supports for the attaching-screws, yet with the exception of the abutments said plate is substantially the same as shown in my application #741,650; or said carrying-plate may be composed of metal, of a substantial thickness and having formed upon its under side the abutments, which with the exception of the abutments is substantially as shown in my application #534,932, in the one instance the carrying-plate being composed of two pieces and in the other instance of a single piece.

Figure 1 is a side elevation of an electro-magnet embodying this invention, in connection with the component parts of a relay. Fig. 2 is a detail partly in section of the magnet-core and pole-piece and attaching-means therefor. Fig. 3 is a vertical section of the lower end portion of the core and pole-piece and carrying-plate. Fig. 4 is a bottom plan view of a portion of the carrying-plate and pole-pieces. Fig. 5 is a bottom plan view of a modified form of carrying plate.

The carrying-plate 20, see Fig. 1, of insulating material, forms the top wall of a housing, and has secured to its under side a metallic plate 145, which forms a support for the armature and other component parts of a relay, all as shown in my said application #741,650, except, as here shown, the metallic plate 145 has formed on its under side a pair of abutments 50, 50, arranged with a space between them to receive the enlarged pole-piece 146, on the core 100. Said abutments 50, 50, however, are not as high as the thickness of the pole-piece, yet are sufficiently high to provide suitable supports for the attaching-screws, as will be described. The core is passed through a hole in the plate 145, and also through a hole in the plate 20 of insulating material, and the pole-piece occupies a position against the under side of the plate 145 between the two abutments 50, 50. Screws 60, 60, extend in diagonal directions through threaded holes in said abutments, and the ends of said screws enter recesses formed in the sides of the core 100, and bear against

the bottoms of said recesses, which form seats for the ends of the screws. It will be observed that said screws are concealed by the housing and also that they do not 5 decrease the area of the pole-piece by extending therethrough and thereby reducing the area of its magnetic field.

In Fig. 5 another form of carrying-plate is represented similar to that shown 10 in my application #534,932, which is made of a substantial thickness and usually of metal, but having formed on its under side abutments 65, 66, between which the enlarged pole-piece 146 is arranged, said abutments being arranged at opposite sides of 15 the hole for the core.

I claim:—

1. In an electro-magnet, a magnet-core having an enlarged pole-piece, and having 20 seats formed in its sides above said pole-piece, a carrying-plate forming the top wall of a housing, having a hole through it for said core and having ribs on its underside arranged adjacent said hole and spaced apart 25 to receive said pole-piece between them, said ribs being of no greater height than the thickness of the pole-piece, and attaching-screws for stationarily holding said core, which extend diagonally upward through 30 threaded holes in said ribs and engage the

seats on the sides of the core, substantially as described.

2. In an electro-magnet, a carrying-plate forming the top wall of a housing comprising an upper and an under plate secured together, both of said plates having alined holes through them, the upper plate having recesses in its underside adjacent the holes therethrough, and the under plate having ribs on its underside arranged adjacent the 40 holes therethrough, which ribs are spaced apart, magnet-cores extended through said holes having enlarged pole-pieces arranged between said ribs and in engagement therewith and with the under plate, and having 45 seats in its sides above said pole-pieces, which seats are disposed in the recesses in the upper plate, and attaching-screws for stationarily securing the magnet-cores to the under plate which extends diagonally upward through threaded holes in said ribs and engage the seats on the cores, substantially as described.

In testimony whereof, I have signed my name to this specification, in the presence of 50 two subscribing witnesses.

ALFRED A. ZIEGLER.
